UNITED STATES PATENT OFFICE

BERNIS M. SHIPLEY, OF DAYTON, OHIO, ASSIGNOR TO THE NATIONAL CASH REGISTER COMPANY, OF DAYTON, OHIO, A CORPORATION OF MARYLAND

DESIGN FOR A CASH REGISTER

Application filed May 23, 1929. Serial No. 31,336. Term of patent 14 years.

To all whom it may concern:

Be it known that I, BERNIS M. SHIPLEY, a citizen of the United States, residing at Dayton, in the county of Montgomery and State of Ohio, have invented a new, original, and ornamental Design for Cash Registers, of which the following is a specification, reference being had to the accompanying drawings, forming part thereof, in which—

Fig. 1 is a perspective view showing the front, right side and top of a cash register showing my new design.

Fig. 2 is a perspective view showing the rear left side and top of the register.

Fig. 3 is a view in side elevation of the register shown in Figs. 1 and 2.

The design is characterized by a machine section seated on a drawer section of greater

superficial area, the upper and lower edges of the drawer section each being circumscribed by a beading rectangular in effect, the machine section having a casing formed into an upwardly projecting flat topped indicator dome, and a downwardly slanted flat keyboard, extending on a downward incline from the foot of the dome to a lower horizontal and forwardly extending printer housing, with rows of keys projecting therefrom and extending from top to bottom of the slanted keyboard.

I claim:

The ornamental design for a cash register as shown and described.

In testimony whereof I affix my signature.

BERNIS M. SHIPLEY.
